US00D911833S

(12) **United States Design Patent** (10) **Patent No.:** **US D911,833 S**
(45) **Date of Patent:** **** Mar. 2, 2021**

(54) **CHILD-RESISTANT PACKAGE**

(71) Applicant: **More Agency, Inc.**, Van Nuys, CA (US)

(72) Inventor: **Mike Toroyan**, Granada Hills, CA (US)

(73) Assignee: **More Agency, Inc.**, Van Nuys, CA (US)

(**) Term: **15 Years**

(21) Appl. No.: **29/700,014**

(22) Filed: **Jul. 30, 2019**

(51) LOC (13) Cl. **09-03**

(52) U.S. Cl.

USPC **D9/416**
